UNITED STATES PATENT OFFICE.

GEORGE W. BRITTON, OF CAMDEN, NEW JERSEY.

BASS DRUM.

No. 886,471.

Specification of Letters Patent.

Patented May 5, 1908.

Application filed May 21, 1907. Serial No. 374,862.

To all whom it may concern:

Be it known that I, GEORGE W. BRITTON, a citizen of the United States, residing at Camden, in the county of Camden and State 5 of New Jersey, have invented a new and useful Bass Drum, of which the following is a specification.

This invention relates to bass drums and more particularly to cymbal attachments and 10 means whereby the cymbal as well as the drum can be sounded in a simple and efficient manner.

A still further object is to simplify and improve the mechanism utilized for this purpose 15 and to so construct it as to permit it to be folded into a compact bundle so that the same can be conveniently carried.

With these and other objects in view the invention consists of certain novel features 20 of construction and combinations of parts which will be hereinafter more fully described and pointed out in the claims.

In the accompanying drawings is shown the preferred form of the invention.

25 In said drawings: Figure 1 is a perspective view of a portion of a drum having a cymbal attachment, embodying the present improvements, connected thereto; Fig. 2 is a longitudinal section through a portion of the 30 beater operating mechanism; Fig. 3 is an enlarged elevation of the cymbal fastening attachment. Fig. 4 is a plan view thereof.

Referring to the figures by characters of reference, 1 designates a drum of any preferred construction. Arranged upon the 35 hoop 2 of the drum head is an angular clamping plate 3 formed at one end with a rigid jaw 4 designed to embrace the hoop 2 while at the other end of the plate is located a pivoted jaw 5. A set screw 6 is disposed within the pivoted jaw and is designed to bear against the plate 3 so that when the screw 6 is tightened jaw 5 will clamp the hoop 2 against the plate 3. An ear 7 is formed integral with 40 and extends from the plate 3 and pivotally connected thereto is a supporting plate 8 having a threaded lug 9 upon which is screwed a rod 10 of desired length and the end of which is suitably fastened to the center of a cymbal 45 11. Ears 12 extend from the plates 3 and 8 and mounted within them is an adjusting screw 13 having a head 14. This screw is designed when tightened, to swing rod 10 and the cymbal connected thereto so that the 50 same can be quickly and accurately adjusted toward or from its beater. The hoop 2 is

also engaged by a pivoted jaw 15 carried by a plate 16 and this jaw has a set screw 17 designed to bear against the plate 16 so that the hoop will be tightly clamped between the 60 jaw 15 and the plate. Ears 18 extend upward from the plate 16 and extending through them are screws 19, the ends of which are swiveled within links 20. A rock arm 21 is fulcrumed between the upper ends 65 of these links, as shown at 22, and carries a head 23 at its upper end in which are inserted the stems 24 and 25 of drum and cymbal beaters 26 and 27 respectively. Set screws 28 serve to secure the stems within the 70 head 23.

The lower end of the rock arm 21 has a slot 29 therein as indicated by dotted lines in Fig. 2 and movably mounted within this slot is a roller 30 extending laterally from a lever 31 75 which is fulcrumed as at 32 between the links 20. The lower end of lever 31 constitutes an abutment for a stem 33 projecting from a piston head 34 slidably mounted within a cylindrical extension 35 on plate 16. A tubular inlet 36 opens into the extension 35 and connected thereto is one end of a flexible hose 37. A compressible bulb 38 is located at the free end of this tube and is provided with a valve 39 of any desired construction designed 80 to prevent the escape of air therethrough when the bulb is compressed but which will automatically open to admit air when the bulb is permitted to expand.

It will be seen that both the cymbal fastening device and the beater fastening device 90 can be readily fastened to the hoop 2 and the cymbal can be easily adjusted to the beater. When the parts have been fastened in position bulb 38 is placed under one foot of the 95 operator and whenever it is desired to beat the drum the bulb is compressed beneath the foot so that the air therein will be forced against the piston 34. The lever 31 will therefore be swung on its pivot so as to throw 100 the two beaters toward the drum, one of them sounding the cymbal while the other strikes the drum. The beaters will immediately rebound and the air will return to the bulb 38 whereupon the operation can be repeated if desired simply by again compressing the bulb. Valve 39 will open automatically to admit any amount of air which may be necessary to make up for leakage. It 105 will be seen that with this device the treadle and other mechanism ordinarily employed for operating the beater is supplanted by the 110

bulb 38 and tube 37 thereby greatly simplifying the construction of the mechanism. When the beaters are not in use the jaw 15 can be disengaged from hoop 2 and by loosening the screws 19 the links 30 can be swung downward and onto extension 35 of plate 16 and stems 24 and 25 detached. The parts will therefore occupy a very small space and can be conveniently carried in the pocket.

10 In order to reduce friction a roller 40 may be mounted upon the end of the rod 33 so as to work within a groove 41 formed in the lower end of lever 31. Although the bulb has been shown provided with a valve it is to be understood that this valve may be located at any desired point in the mechanism provided the same can produce the desired results.

What is claimed is:

- 20 1. An attachment for drums comprising drum engaging means, a rock arm supported thereabove and connected thereto, a beater carried thereby, a piston for actuating the rock arm, and means for directing fluid against the piston.
- 25 2. An attachment for drums comprising a rock arm, a beater carried thereby, means for connecting the arm to a support, a piston for actuating the arm and beater, and means for directing fluid against the piston.
- 30 3. An attachment for drums comprising a rock arm, a pivoted support therefor, a beater carried by the arm, a piston, means for transmitting motion from the piston to the rock arm, and means for directing fluid against the piston to actuate it.
- 35 4. An attachment for drums comprising drum engaging means, a supporting device pivotally connected thereto, a rock arm

mounted upon the supporting device, a beater carried by the rock arm, and fluid actuated means for operating the rock arm.

5. An attachment for drums comprising drum engaging means, a supporting device pivotally connected thereto, a rock arm mounted upon the supporting device, a beater carried by the rock arm, an intermediate lever movably engaging the rock arm, and fluid actuated means for actuating the lever.

6. An attachment for drums comprising drum engaging means, a supporting device pivotally connected thereto, a rock arm mounted upon the supporting device, a beater carried by the rock arm, an intermediate lever movably engaging the rock arm, a piston for actuating the lever, and fluid operated means for actuating the piston.

7. The combination with a plate, and means for securing the same to a drum; of supporting members pivotally connected to the plate and disposed to fold upon the plate, means for securing said members against movement, a rock arm pivotally mounted between said members, a beater carried thereby, a cylindrical extension upon the plate, a piston therein, mechanism operated by the piston for actuating the rock arm, and means for directing fluid under pressure against the piston.

In testimony that I claim the foregoing as my own, I have hereto affixed my signature in the presence of two witnesses.

GEORGE W. BRITTON.
